Primary Examiner — Rhea Shields

(57) **CLAIM**

The ornamental design for a display screen with graphical user interface having a wheel selector, as shown and described.

DESCRIPTION

FIG. 1 is a front view of an exemplary representation of our new design; and,

FIG. 2 is a front view of another exemplary representation thereof.

In the drawings, the broken lines are for the purpose of illustrating portions of the display screen with graphical user interface that forms no part of the claimed design.

1 Claim, 2 Drawing Sheets

FIG. 1

FIG. 2
